UNITED STATES PATENT OFFICE

HERBERT S. BRIDGE, OF CINCINNATI, OHIO, ASSIGNOR TO THE CRANE & BREED
CASKET COMPANY, OF CINCINNATI, OHIO, A CORPORATION OF OHIO

DESIGN FOR A DRAPED BURIAL CASKET

Application filed December 13, 1929. Serial No. 33,784. Term of patent 14 years.

To all whom it may concern:

Be it known that I, HERBERT S. BRIDGE, a citizen of the United States, residing in Cincinnati, in the county of Hamilton and State of Ohio, have invented a new, original, and ornamental Design for Draped Burial Caskets, of which the following is a specification, reference being had to the accompanying drawing forming part thereof, in which—

Fig. 1 is a perspective view, viewed from the front, of a draped burial casket showing my new design, the casket being shown open; and,

Fig. 2 is a plan view of the same.

I claim:

The ornamental design for a draped burial casket, substantially as shown and described.

HERBERT S. BRIDGE.
